(57) **CLAIM**

I claim the ornamental design for a shoe sole, as shown and described.

DESCRIPTION

FIG. 1 is a perspective view of a shoe sole where the bottom surface is visible.

FIG. 2 is a bottom view of the bottom surface of the shoe sole.

FIG. 3 is a top view of the top surface of the shoe sole.

FIG. 4 is a side view of one side of the shoe sole.

FIG. 5 is a side view of another side of the shoe sole.

FIG. 6 is a back view of the shoe sole. The shoe sole is positioned with the bottom surface facing upward; and,

FIG. 7 is a front view of the shoe sole. The shoe sole is positioned with the bottom surface facing downward.
